LINGERIE STRAP HOLDER

Julia A. St. Clair, San Francisco, Calif.

Application September 11, 1937, Serial No. 163,474

1 Claim. (Cl. 24—85)

This invention relates to holders for lingerie and other garments, and more particularly to a means for supporting and holding the straps which support lingerie or other under-garments from the shoulders of the wearer.

It is well known that the shoulder straps for supporting garments in proper position from the shoulders of the wearer, have, unless some means is provided to prevent it, a tendency to slip over the shoulders or become misplaced, whereby the garment is unsupported and falls, to the great discomfort of the wearer. In order to obviate this condition other devices have been devised, but so far as known all of such devices have had some difficulty, either because of their insecure attachment to the under-garment, or by reason of some defect in the portion of the device which supports the lingerie strap.

It is an important object of the present invention to obviate all of the difficulties heretofore found to exist, and to overcome the inconveniences known to be present in devices of the character referred to, and to the accomplishment of these results the present invention consists of the device as hereinafter more fully described, the novel features thereof being pointed out in the appended claim.

In the accompanying drawing:—

Figure 1 is a perspective view of a lingerie holding or supporting device embodying the present invention, and

Figure 2 shows the same device in side elevation.

Referring to the drawing, the numeral 1 illustrates one of the bars of a safety pin wherein the wire thereof is at one end of the device formed into a coil 3 having a terminal member 5 provided at its end with a point 7. At the opposite end of the bar 1 from which the coil 3 is formed, a protecting sheath or guard 9 is provided, made of suitable metal and provided at its lower portion with a return bend 11 which is adapted to receive the point 7 of the pin when said pin has been inserted in the garment, and it is desired to protect the point and sheath it so as to prevent injury to the garment or person by accidental contact with said point.

The bar 1 of the device, after leaving the coil 3, passes through the upper bent over metal portion 12 of the sheath 9, and continues thence, being formed beyond the sheath in a return bend 15 which is thence directed as a bar 17 in substantial parallelism with the bar 1, and finally at the end is turned over or doubled in the form 55 of a loop 19, the final terminal end portion 20

of the upper bar 17 being caused to engage or abut the body of said bar, as shown in the drawing. By the construction described it will be seen that the final bar 17 of the wire or stock metal is bent first to form an enclosing loop portion 21 to receive the strap of the lingerie, while its terminal portion is reversely bent back upon itself to form a second loop 19, which latter contacts with the bar 1 at the point 23, or with the loop 3 at such a point so as to form a closure of the space between the bars 1 and 17, such enclosed space effectively serving to receive and house and retain in position the lingerie shoulder strap, so that the same is not permitted to escape while having sufficient lateral play to conform to all of the necessary movements brought about by changes in the position of the body of the wearer, etc.

A very valuable feature of the invention resides in the return loop portion 19. This loop not only serves by engagement with the bar 1 or 20 coil 3 at the left hand end of the device as viewed in Fig. 1, to securely enclose a space 21 for retaining the lingerie strap, but also forms a smooth terminal portion for the bar 17. The loop 19 serves thus to effectually confine the strap 25 and at the same time does not present an unfinished or projecting end to the bar for engagement with those portions of the garment which overlie the device, or possible injury to the hand of the wearer in adjusting the strap within or 30 removing it from the space 21 of the loop, which would be the case were a safety pin point present where the loop 19 is located.

It is to be observed that in this device what may be regarded as the safety pin element, including the lower bar with pin point 7, shield or guard 9, and loop 3, is utilized for the purpose of securing the lingerie holder as an entirety to the hem or other suitable portion of the under-garment, while the upper portion of the device, 35 comprising the loop 21, and the return bend 19, is utilized entirely in the performance of the function of retaining the lingerie strap in position. In the performance of this last-named function, it will be seen that the lingerie strap 40 may, by a simple lateral movement against the extreme end portion of the loop 19, be passed within the space 21, the bar 17 flexing slightly to permit a sufficient opening of the space between the coil 3 and loop 19 to permit the strap 50 to enter. It will be further seen that by a reverse movement of the lingerie strap in removing the same from the device, the strap need be simply pressed against the inside portion of the loop 19, thereby causing a separation of the loop from 55

the coil 3 again, while the strap is being removed, the parts instantly snapping back into their normal position after such removal. No points, unguarded ends, or portions of the device which might cause injury to the fingers or garments are embodied in that portion of the holder which is used to retain the lingerie strap in position, and prevent its accidental removal, as the resiliency of the wire of which the device is made is sufficient to maintain contact between the loop 19 and coil 3 during all normal movements of the wearer which would have any tendency to cause the strap to be accidentally disengaged from the holder. At the same time, very slight pressure against the strap would be sufficient to cause it to move, either into or out of the space 21 by displacement of the loop 19 from the coil 3, by the user.

It will also be seen that the device comprises but a single, continuous piece of wire, or metal stock, which is formed into both the pin portions 5, 7, the loop 3, and the bar 1, which latter is continued to form the bar 17 and loop 19. The entire device, accordingly, consists of only two pieces, namely, the wire which is bent to form the parts above described, and the sheath or

guard 9 which is secured to the wire, and is in position to guard the point of the pin 7 when said pin is closed, as the device is fastened upon the garment.

The right is reserved to make such changes in the details of construction of this device as will be comprehended by the scope of the invention as set forth by the following claim.

I claim:—

A lingerie holder made of a single piece of wire stock and comprising a bar member having a terminal point, said member being formed into a coil at a suitable distance from the point and extending thence in substantial parallelism with the bar member to provide a second bar member, then reversed upon itself in a single U-bend to provide a third bar member spaced and terminating in a closed loop which is resiliently held in contact with said coil, in combination with a sheet metal guard permanently and rigidly attached to the second bar member by having portions doubled over to enclose the wire of said member in proximity to said bend and provided with a receiving portion for the pin point when the pin is closed.
